C. STELLER & E. N. CLARK,
MOP WRINGER,
APPLICATION FILED JAN. 17, 1912.

1,044,101.

Patented Nov. 12, 1912.

UNITED STATES PATENT OFFICE.

CHARLES STELLER AND EDDY N. CLARK, OF SEATTLE, WASHINGTON.

MOP-WRINGER.

1,044,101.

Specification of Letters Patent. Patented Nov. 12, 1912.

Application filed January 17, 1912. Serial No. 671,771.

To all whom it may concern.

Be it known that we, CHARLES STELLER and EDDY N. CLARK, citizens of the United States, residing at Seattle, in the county of King and State of Washington, have invented certain new and useful Improvements in Mop-Wringers, of which the following is a specification.

Our invention relates to that class of mop-wringers which are employed with and attached to scrubbing pails.

The object of the invention is the improvement in devices of this character whereby a mop may be more thoroughly and expeditiously dried while safeguarding the mop yarns or cloth from being torn by becoming entangled about the roller axles of the wringer.

The invention is illustrated in the accompanying drawings, in which—

Figure 1 is a side elevation of a pail provided with the present invention. Fig. 2 is a plan view thereof. Fig. 3 is a vertical transverse section of the same. Fig. 4 is a longitudinal vertical section, and showing the wringer in use. Fig. 5 is a fragmentary perspective view to illustrate principally the manner of connecting the movable rollers to the operating lever.

The reference numeral 1 designates a scrubbing-pail provided with a bail 2 and having at the rear and near its bottom a stirrup-piece 3, as usual. Provided interiorly of the pail and adjacent to its top is a pair of plates 4 whose central portions are arranged parallel to each other and their extremities 5 fitted against the inner periphery of the pail whereby the plates are secured thereto, as by rivets 6. Disposed one above the other, and in spaced relations, is a pair of transversely arranged rollers 7 and 7' whose axles 8 are journaled in holes provided in the plates 4 and near the front ends thereof.

9 and 9' are a pair of rollers having axles 10 and 10' extending respectively through guide slots 11 and 11' provided in the plates and journaled in yokes 12. Intermediate of the journal bearings for axles 10 and 10', each yoke is pivotally connected by a pin 13 with a branch 14 of an angle lever which is fulcrumed to studs 15 projecting from opposite sides of the pail and in proximity to its bottom. Forwardly from such fulcrum studs the other arm 14' of the lever is

of a circular form to extend about the front of the pail.

16 is a foot piece advantageously provided on the arm 14' and wherewith the lever is most conveniently actuated by the operator's foot to overcome the power of a helical spring 17, Fig. 1. The guide slots 11 and 11' are formed in their plates to be concentric or nearly so with respect to the fulcrum of said lever. All of the aforesaid rollers 65 are of lengths to be slightly less than the distance between the opposing faces 4' of the plates 4 and to ward off the yarn or strands of a mop from entering the interstices between the various rollers and the 70 plates we provide flanges 18 and 18' along the upper and lower edges of the plates. The flanges protrude inwardly and are desirably formed to be concentric to the axis of the lever fulcrum. As shown in Figs. 3 75 and 5, a leaf spring 20 is desirably interposed between each of the yokes 12 and an ear 14" provided on the associated branch of said lever. The purpose of these springs is to yieldingly maintain the yokes in sub- 80 stantially upright positions subject, however, to the constraining effect of the guide slots 11 and 11' which accommodates the axles of the movable rollers 9 and 9' and guide the latter to present them to the complementary rollers 7 and 7' in the relative positions in which they are shown in Fig. 4.

In operating the invention, the mop M is put into the water contained in the pail and between the pairs of rollers when the same are separated. The operator then pushes down with his foot upon the attachment 16 to cause the lever to be swung to carry rollers 9 and 9' against the mop and while the pail is being held by the operator's other foot pressing upon stirrup 3. When the rollers 9, 9' encounter the mop the arms of the springs 20, which normally support the yokes 12 against tilting, will allow the yokes to yield for one or the other of the referred to rollers to accommodate any knots or other unevenness in the mop as the latter is drawn upwardly to squeeze the water therefrom through power exerted by the operator's foot in manipulating the lever.

What we claim, is—

1. The combination with a pail having plates rigidly secured thereto and provided with guide-slots, and a pair of rollers having their axles journaled in said plates, of a 110

second pair of rollers having their axles extend through the respective guide slots, an angle lever fulcrumed to studs provided on the pail, and yokes affording journal bearings for the axles of the last named rollers and pivotally connected intermediate of such journal bearings to branches of said lever.

2. The combination with a pail having plates rigidly secured thereto and provided with guide-slots, and a pair of rollers having their axles journaled in said plates, of a second pair of rollers having their axles extend through the respective guide slots, an angle lever fulcrumed to studs provided

on the pail, yokes affording journal bearings 15 for the axles of the last named rollers and pivotally connected intermediate of such journal bearings to branches of said lever, and a spring for each of said yokes and tending to maintain the latter in upright 20 positions.

Signed at Seattle, Wn., this 2nd day of January 1912.

CHARLES STELLER.
EDDY N. CLARK.
